UNITED STATES PATENT OFFICE.

ROBERT ELCOCK, OF JOHANNESBURG, TRANSVAAL, SOUTH AFRICA.

CLOTHES-WASHING MACHINE.

1,356,423.

Specification of Letters Patent.

Patented Oct. 19, 1920.

Application filed August 28, 1918. Serial No. 251,785.

To all whom it may concern:

Be it known that I, ROBERT ELCOCK, a British subject, residing at Illovo Buildings, Pretoria Bridge, Johannesburg, Transvaal Province of the Union of South Africa, have invented certain new and useful Improvements in Clothes-Washing Machines, of which the following is a specification.

The present invention relates to machines for washing clothes and the like of the kind in which the articles to be washed are mechanically agitated with detergent liquid.

A purpose of the invention is to provide such a machine in which the liquid and clothes are agitated back and forth without substantial lifting, thereby making the machine light to work. Another purpose is to cause the liquid to flow relatively to, and through, the fabrics by mechanical means. A further purpose is to subject the clothes to combined squeezing and rubbing to express the dirt and to a vibratory movement of the liquid which tends to keep the fabrics spread and thus freely permeable by the liquid.

The invention is illustrated in the accompanying drawings in which,

Fig. I is an elevation showing part of the front wall of the tub removed. Fig. II is a vertical section on XX Fig. III with the parts differently positioned from Fig. I.

Fig. III is a partial plan. The lid of the tub is omitted in Figs. II and III.

The apparatus comprises a tub 1 which is rectangular in plan and the ends 2 of which preferably slope together downwardly.

In the supporting frame 3 provision is made for mounting a detachable stove 4 by means of which the contents of the tub may be heated if desired.

5 is an operating handle carried on a bail 6 fast to a shaft 7 pivoted to the tub so that the handle may be oscillated up and down. On the shaft 7 is fixed an arm 8 to which is connected a tension spring 9 attached at its lower end to a hook 10 on the tub; said spring returning or assisting to return the bail 6 after it has been pressed down. The

spring 9 may be hooked into any one of a number of holes 11 on the arm 8 to adjust its effective force. It will be evident that the bail 6 may if desired be reciprocated by power.

At each side arm of the bail 6 is pivoted

an upright rod 12 which is loosely guided for vertical movement by a guide 13 on the side of the tub. To the upper end of each such rod 12 are pivoted the two links 14, 14 of a toggle. Said links are pivoted at their other ends to the oscillating dash plates 15, 15^a, which plates are duplicates of one another. They are pivoted at their lower ends by pintles 16 which simply drop into slots 17 in the bearing blocks 18 fixed to the floor 65 of the tub toward each side.

At the ends of the tub are the rising dash plates 19, 19^a. The rising dash plate 19 at the left hand side is mounted upon arms 20 extending from the reciprocating dash plate 15^a at the right. Similarly the rising dash plate 19^a on the right is mounted on arms 20^a extending from the reciprocating dash plate 15 on the left. The upper ends of the rising dash plates are fitted with slippers 21 75 which run on balls 22 secured inside the end walls of the tub.

The spaces 23 between each oscillating dash plate and the adjacent rising dash plate constitute the washing chambers. The 80 lower end of each such chamber is closed in sufficiently to retain the fabrics by a partition 24 which extends from the plate 19 (or 19^a) and works over a curved partition 25 extending from the adjacent plate 15 (or 15^a). 85 The shape of the partition 25 is such that the aperture between it and the lower edge of the partition 24 is not varied by the relative movement of the plates 15 and 19. It is preferred to leave an aperture between the partitions 24 and 25 to cause a jet of liquid 90 as hereafter mentioned.

26 is a deflection plate which assists circulation of the liquid due to heating from the stove 4 by guiding the uprising and 95 heated currents of liquid to the chambers 23.

In use the tub is charged with washing liquid and the clothes are placed in the chambers 23. Upon the handle 5 being reciprocated, at each downward movement of the handle the plates 15, 15^a are moved outwardly toward the opposite ends of the tub as indicated in Fig. II and upon the handle being raised they return to their original positions. The capacity of each chamber 100 105 23 is thus alternately diminished and increased, so causing the liquid to flow into and from said chambers to agitate and penetrate the clothes which are retained therein. If a suitable aperture is left between the plates 110

24 and 25, a considerable jet of liquid flows up through the same and impinges on the clothes, when the plates 15 are retracted. Moreover at each outward stroke of the 5 plate 15 the clothes are squeezed between such plate and the plate 19. At the same time plate 19 rises and afterward descends and so causes a rubbing action on the clothes between the plates. It will be noted that at 10 the end of the outward stroke of the plate 15 when the clothes are squeezed, the toggle 14 is in the position of its greater leverage so that considerable pressure can be exerted without the exercise of undue force at the 15 handle.

The separating movement of the plates 15 and 19 sets up a sort of expansive tendency in the liquid contained in the clothes which operates to open out the latter and not only 20 prevents them from remaining bunched up but also causes them to be differently disposed when squeezed at the next stroke, so insuring cleansing of all portions. The rubbing action of the plates 19 also assists the 25 operation. It will be noted that the toggle gives a quick final return movement of the plates which assists this spreading action.

The space 27 between the plates 15 and 15^a can be used for soaking and agitating clothes 30 before they are put into the washing chambers 23.

Upon detaching the four toggle links 14 from the plates 15, said plates 15 together with the plates 19 may be lifted out of the 35 tub, so permitting all parts to be efficiently cleansed. A cock 28 is provided for drawing off the used liquid.

I claim:

1. In a washing machine, the combination 40 with a tub, of substantially vertically reciprocating dash plates, and a pair of oscillating dash plates between the reciprocating

dash plates and connected with and operating the same.

2. In a washing machine, the combination 45 with a tub, of a pair of oscillating dash plates arranged for opposite movement, arms extending from each of said plates and dash plates arranged for rising and falling movement mounted on said arms. 50

3. In a washing machine, the combination with a tub, of a pair of oscillating dash plates, a reciprocating actuating member, and toggle links connecting said reciprocating member to the plates whereby the latter 55 are alternately separated and retracted as the reciprocating member is reciprocated.

4. In a washing machine, the combination with a rectangular tub, of an oscillating plate extending across said tub, a vertical 60 rising and falling plate extending across said tub, the space between said plates and the wall of the tub forming a washing chamber, and coöperating partitions extending severally from each of said plates and serving substantially to close the bottom of said chamber. 65

5. In a washing machine, the combination with a tub of relatively oscillated dash plates therein forming with the walls of the tub a 70 washing chamber, coöperating partitions on said plates serving as a bottom for the chamber, said partitions providing between them an aperture through which liquid passes jetwise upon relative movement of the plates. 75

6. In a washing machine the combination with a tub, of dash plates having sliding engagement with the sides of the tub, a pair of oscillating dash plates at about the center of the tub, and a connection between the first 80 named plates and the oscillating plates for operating the former from the latter,

In testimony whereof I affix my signature.
ROBERT ELCOCK.
